UNITED STATES PATENT OFFICE

OSCAR LEE, OF WAUPUN, WISCONSIN

WHISK BROOM

Application filed March 14, 1930. Serial No. 435,926.

This invention relates to improvements in brooms, and more particularly to whisk brooms and the method of making the same.

The object of the present invention is to provide a whisk broom which shall comprise fibers fabricated in a novel manner to produce a more desirable and useful product.

Another object of the invention is to provide a broom of the character designated in which individual bunches of colored fibers shall be assembled and incorporated therein to produce any desired artistic color effects in the finished article.

A further object of the invention is to provide a broom of the character designated which shall be simple in construction and more cheaply manufactured than similar articles heretofore produced.

These and other objects of the invention will be more manifest from the following description and drawings, and specifically set forth in the claims.

In the drawings—

Figure 1 is a perspective view of a fabricated loop of fibers which forms the first step in the novel process forming the subject of the present invention;

Figure 2 is a perspective view showing separate bunches of fibers of different colors assembled to form the broom body;

Figure 3 is a similar view showing the completed body portion and the finished top.

Figure 4 is a similar view to Figure 3 with the addition of the wrapped binder for the upper body portion of the broom;

Figure 5 illustrates the manner of applying additional bunches of fibers to the body portion illustrated in Figure 4;

Figure 6 illustrates the outer bunches in assembled form;

Figure 7 shows the final wrapping of the additional fibers to form the handle portion;

Figure 8 is a longitudinal view of the completed brush illustrated in Figure 7;

Figure 9 is a top plan view of the brush shown in Figure 7; and

Figure 10 is an end view showing a design produced by the different colored bunches comprising the broom structure.

Referring to the drawings, there is shown

the several novel steps employed in making a broom in accordance with the present invention. The preliminary steps are illustrated in Figures 1, 2 and 3 in which long strands of raw wood, for example fibers, are collected in different bunches and secured intermediate their ends so that all the fiber material may be subsequently incorporated in a broom.

The primary step in fabricating the broom in accordance with the present invention includes the selection of individual bunches of fibers indicated by numerals 10, 11 and 12 and permanently binding the bunches intermediate their ends by a binder member 13 so as to form a round broom of a size that may be conveniently grasped by the hand. This binder may be of any suitable material wrapped around the bunches, such as a cord or wire and the like. In the present construction, cord is employed as the binder throughout the broom construction. If it is desired to provide a hanger for the broom, a braided loop 14 with a knot 24 is provided and bound in with the bunches when they are first assembled as shown in Figures 2 and 8. After the bunches are thus securely bound, they are then folded double over the binder member 13 and distributed so as to form a neatly rounded bead or head 15. The bunches thus assembled and folded are then temporarily held in place by fastening members 16 and 17. When the fibers are properly arranged in a uniform manner, a permanent covering of cord 18 is wrapped around the upper portion of the broom and securely binds the fibers and also forms a convenient handle. This covering extends from the bead at the top portion of the broom to a point about midway the length thereof as shown in Figure 4. It has been found that by tightly wrapping a cord binder around the bunches of fibers they are firmly bound together and permit sufficient resiliency to minimize any working out or breaking of the fibers when the broom is in use.

The lower end of the broom is increased in size by adding other individual bunches of fibers 19 and 20 as shown in Figure 5.

When these bunches are thus assembled they are bound intermediate their ends by a suitable binder 21. The bunches thus assembled are then folded double in a manner 5 similar to that employed in the first steps of the fabrication of the broom. The bunches are then folded over this binder and are permanently secured in place by a wrapped covering 22. This wrapping is 10 preferably co-extensive with the lower portion of wrapping 18 as shown in Figures 7 and 8 so as to form a firm fastening so that all the fibers shall have substantially the same point of flexure. The particular manner 15 of binding the fibers together by inner and outer covering members 18 and 22 provides a rigid broom that will effectively prevent the loosening of the fibers. This form of covering also minimizes any danger of 20 broken fibers injuring the hands when the brush is in use. When the outer bunches of the fibers are thus folded and secured in place, a second or intermediate bead 23 is formed midway of the handle and this bead 25 provides an additional convenient grip on the handle and also adds to the symmetrical proportions and appearance of the finished article.

Another novel feature of the present invention is that of providing bunches of fibers 30 of different or contrasting colors so that any desired artistic designs and color schemes may be obtained by selecting individual bunches of the desired color. One form of 35 design is shown in Figure 9 in which the outer bunches of fibers are each of a different color. In Figure 10 the outer fibers are all of the same color and the central bunches of fibers are of a different color. By thus 40 incorporating bunches of fibers of differently colored proportions in a unit construction, I am able to produce a broom which shall be more durable in construction and possess the desired artistic and attractive 45 appearance.

While I have shown and described a preferred embodiment of the invention, it is obvious that various changes may be made therein without departing from the scope 50 of the invention as set forth in the appended claims.

In the claims:

1. As an article of manufacture, a whisk broom comprising a plurality of individual 55 bunches of fibers folded intermediate their ends, a loop of fibers extending outwardly beyond the top of said folded portion, a wrapped covering for the upper portion of said bunches to form the same into a substantially 60 circular broom, another group of folded fibers placed around the lower portion of said wrapped covering and extending to the lower end of the broom, and another wrapped covering extending from the 65 folded end portion of said second group of

fibers to the lower portion of said first wrapped covering.

2. As an article of manufacture, a whisk broom comprising a plurality of bunches of fibers folded intermediate their ends, a wrapped covering for the upper portion of said bunches to form the same into a substantially circular broom, another group of folded fibers placed around the lower portion of said wrapped covering and extending to the lower end of the broom, and another wrapped covering extending from the folded end portion of said second group of fibers to the lower portion of said first wrapped covering.

In testimony whereof I affix my signature.

OSCAR LFE.
